CHRISTMAS NATIVITY STABLE

Salvatore R. Saia, Detroit, Mich.

Application November 26, 1954, Serial No. 33,255

Term of patent 14 years

(Cl. D34—15)

Fig. 1

Fig. 2

Fig. 3

Fig. 1 is a front elevational view of a Christmas nativity stable showing my new design;

Fig. 2 is a side elevational view thereof; and

Fig. 3 is a top elevational view of said Christmas nativity stable.

I claim:

The ornamental design for a Christmas nativity stable, as shown.
